United States Patent Office

Des. 179,019
Patented Oct. 23, 1956

179,019

PAIR OF EYE-GLASSES OR SIMILAR ARTICLE

James T. Mangan, Evergreen Park, Ill.

Application February 10, 1956, Serial No. 40,104

Term of patent 7 years

(Cl. D57—1)

FIG. 1

FIG. 2

Fig. 1 is a front perspective view of a pair of eye-glasses or similar article showing my new design.

Fig. 2 is a rear and inverted perspective view thereof.

I claim:

The ornamental design for a pair of eye-glasses or similar article, substantially as shown.
